United States Patent Office

Des. 205,455
Patented August 9, 1966

205,455

LASER PHOTOCOAGULATOR

John T. Armbruster, Niagara Falls, and Irwin A. Bosack,
Buffalo, N.Y., assignors to American Optical Company,
Southbridge, Mass., a voluntary association of Massa-
chusetts

Filed Nov. 4, 1964, Ser. No. 82,467

Term of patent 14 years

(Cl. D26—14)

Fig. 1

FIG. 1 is a front perspective view of a laser photocoagulator showing our new design;

FIG. 2 is a rear elevational view thereof; and

FIG. 3 is a side elevational view thereof.

The essential features of our design are shown in full lines in the drawings.

We claim:

The ornamental design for a laser photocoagulator, as shown and described.
